US00D406901S

United States Patent [19]

Ditterline et al.

[11] Patent Number: Des. 406,901

[45] Date of Patent: **Mar. 16, 1999

[54] AUTOMATIC IMMUNOASSAY ANALYZER

[75] Inventors: **Andy Ditterline**, Arlington, Tex.; **Dave Staal**, Grayslake; **George Maliekal**, Lake Zurich, both of Ill.; **Steve I. Hwang**; **Max Yoshimoto**, both of San Francisco, Calif.; **Rob Bernstine**, Chesapeake City, Md.

[73] Assignee: **Abbott Laboratories**, Abbott Park, Ill.

[**] Term: **14 Years**

[21] Appl. No.: **73,169**

[22] Filed: **Jul. 2, 1997**

[51] LOC (6) Cl. **24-01**

[52] U.S. Cl. **D24/232**; D10/81; D24/231; D24/186

[58] Field of Search **D24/232, 231, D24/186; 436/50, 43, 47; 472/63, 64, 67; D10/81**
